(57) **CLAIM**

The ornamental design for a shoe as shown and described.

DESCRIPTION

FIG. 1 is a front, left and top perspective view of a shoe, showing my new design.

FIG. 2 is a front, right and top perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a rear elevation view thereof; and,

FIG. 8 is front elevation view thereof.

The shoe for the left foot is a mirror image of the shoe for the right foot as shown in FIGS. 1 to 8, and is also claimed.

1 Claim, 8 Drawing Sheets
